COMBINED MULTIPLE SOCKET PATCHBOARD AND FRAME

Robert Frederick Oxley, Priory Park, Ulverston,
Lancashire, England

Filed Apr. 4, 1968, Ser. No. 11,303

Term of patent 7 years

Int. Cl. D13—03

U.S. Cl. D26—1

FIG. 1 is an isometric front view of a combined multiple socket patchboard and frame from one side and above; and

FIG. 2 is a rear isometric view thereof from the opposite side and above.

The appearance of the undisclosed bottom is substantially identical to the disclosed top.

I claim:

The ornamental design for a combined multiple socket patchboard and frame, substantially as shown and described.
